UNITED STATES PATENT OFFICE.

MILTON F. WILLIAMS, OF ST. LOUIS, MISSOURI, ASSIGNOR TO WILLIAMS PATENT CRUSHER & PULVERIZER COMPANY, OF ST. LOUIS, MISSOURI, A CORPORATION OF MISSOURI.

CRUSHER AND PULVERIZER.

1,420,354.

Specification of Letters Patent. Patented June 20, 1922.

Application filed October 28, 1921. Serial No. 511,063.

To all whom it may concern:

Be it known that I, MILTON F. WILLIAMS, a citizen of the United States, residing at St. Louis, State of Missouri, have invented 5 certain new and useful Improvements in Crushers and Pulverizers, of which the following is a specification.

This invention relates to certain new and useful improvements in crushers and pulverizers, the peculiarities of which will be hereinafter fully described and claimed.

The main object of my invention is to provide an arcuate cage having a series of cove serrations of such form that the material passing into the grinding chamber and driven off tangentially from the ends of the hammers, will be diverted from said tangential direction to practically a radial direction over renewable cutting edges of relatively harder material and thus transversely 20 to the hammer circle which is in close proximity to said cutting edges,—and as the material successively passes from cove to cove around the cage, and is returned again and again by said coves into the path of the hammers it is successively reduced upon the sharp edges of the cage coves in conjunction 25 with said hammers; and second to graduate the size of the renewable pieces of said 30 cove serrations in diminishing ratio in the direction of rotation of the rotor to accord with the successive fineness of the material being reduced.

In the accompanying drawing on which 35 like reference letters indicate corresponding parts, Fig. 1 represents a vertical sectional elevation across the shaft of a machine exemplifying my invention; and Fig. 2 a sectional perspective view of a portion of my 40 cove serrated cage.

The letter A designates a rotor shaft, and B hammers preferably pivoted on discs C or other suitable hammer mounts. A suitable casing D is provided with a hopper E above 45 the rotor chamber, and a suitable metal catcher F of the saw-tooth or other variety is mounted on the casing adjacent to the hopper.

Mounted in the casing preferably 50 concentric with rotor, is a cage extending more or less around on the inside of the grinding chamber and provided with series of cove serrations on its inner face,—each cove having a plane surface G tangent to the hammer circle or substantially so, and also hav-

ing a plane surface H substantially radial to the rotor shaft and these planes connected by a curved surface I set back away from the hammer circle. This curved surface thus located intermediately of the lateral surface on both sides of it and thus alternating with the cutting edges, acts to deflect the material driven off tangentially from the ends of the hammers, and divert such material back again into the rotor 60 chamber in a substantially radial plane as the material leaves the cove and into the path of the hammers traveling in close proximity. The radial plane surface H in each cove intersects the adjacent tangent plane 65 surface G of the next cove in a sharp cutting edge which I have preferably provided with a cutting piece of relatively harder material inserted at said intersection so as to form a renewable cutting edge. This 70 insert piece may be of two legs J—J' having intersecting surfaces meeting in an acute angle forming a cutting edge. One of the legs J is held in position by fastening means such as screws K or otherwise, as shown in 75 Fig. 2. One leg lies in a recess back of said tangential plane surface of a cove and the other leg J' fits in a radial slot at the end of the cove so that only a portion of it near the sharp edge blends with the curved plane 80 surface I that overlaps the radial surface and that deflects the material across the cutting edge into the path of the hammers.

Referring to Fig. 1 it will be seen that the 85 cove serrations gradually diminish in size in the direction of rotation so as to correspond to the fineness of the material being reduced; that is to say, the material entering the chamber is comparatively coarse and is met by the hammers which drive it into 90 comparatively large coves which reduce it, and as it passes from cove to cove and across successive cutting edges it is repeatedly reduced to greater fineness. The cage with 95 cove serrations is followed by a cage of 100 perforated metal L and a screen wire cage M of suitable size to take care of the material ground fine enough to be discharged through the openings. Any material not passing through these openings or otherwise 105 discharged from the rotor chamber, is carried upward by the hammers and further ground upon the upper portion of the cage which is mounted in the cover of the casing. Cove 110 serrations of similar forms to those of above

described but preferably somewhat finer than those next to the discharge cage, are formed on the inner face of this upper cage portion which is preferably hinged at N 5 near the hammer circle and horizontal plane through the shaft, and is adjustable at the opposite end by any suitable means,—such as a bolt O extending through the cover and having a head engaging the upper end of 10 this cage portion to pull it outward, while another bolt P threaded into the cover acts compressively on the said end of the cage portion. Jam nuts are preferably provided on said bolts.

15 Another portion of the cage having cove serrations may be adjustable by mounting it on a slideable block Q operated by an adjusting bolt S, so that said cage portion carried by said sliding block, can be adjusted 20 to and from the hammer circle.

I claim:

1. In a pulverizer or disintegrator, the combination with a rotor, of a casing disposed eccentrically with respect thereto

whereby to provide a gradually diminishing 25 space between said rotor and said casing, said casing having a series of reentrant angles of gradually diminishing depths disposed around the face of the casing, said angles having rounded bottoms and the 30 shorter side of said angles extending radially of the rotor.

2. The combination as in claim 1, further characterized by a removable angular impinging member disposed along each of the 35 ribs formed by the intersection of the short and long sides of the adjacent angles.

3. The combination as in claim 1, further characterized by a series of removable angular impinging members of gradually decreasing 40 sides disposed along the ribs formed by the intersection of the short and long sides of adjacent angles, said ribs having cut-outs to form seats for said members.

In testimony whereof I have affixed my 45 signature.

MILTON F. WILLIAMS.
